(57) **CLAIM**

The ornamental design for a bicycle carrier, as shown and described.

DESCRIPTION

FIG. 1 is a front, top, and right-side perspective view of a first embodiment of a bicycle carrier showing the new design;

FIG. 2 is a rear, bottom, and left-side perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The dashed lines and structure they depict form no part of the claimed design.

1 Claim, 8 Drawing Sheets
